ELECTRICAL CONNECTOR

Frederick W. Mebold, St. Louis, Mo., assignor to
 James R. Kearney Corporation, St. Louis, Mo.,
 a corporation of Missouri

Application October 9, 1939, Serial No. 298,525

6 Claims. (Cl. 287—49)

This invention relates generally to connectors adapted for use in mechanically and electrically connecting electrical conductors in the construction, repair, extension, and maintenance of electrical systems, such as telephone, telegraph, light, and power systems, and more specifically to connectors of the split-bolt type which are of improved construction and arrangement, the predominant object of the invention being to 5 provide an improved connector of the type mentioned which, because of its unique construction and arrangement, is capable of economical production and efficient and convenient operation in use.

15 Fig. 1 is an end elevation of the improved connector showing same in association with a pair of connected conductors, one of which is shown in section.

Fig. 2 is a vertical section taken on line 2—2 20 of Fig. 1.

Fig. 3 is a plan view of the connector shown in Figs. 1 and 2 with a portion of the connector shown in section, and with the conductors absent.

25 Fig. 4 is a perspective of the follower of the connector illustrated in Figs. 1, 2, and 3.

Fig. 5 is a side elevation of a slightly modified form of the invention with a portion of the connector shown in section, the follower of the connector shown in Fig. 5 being operatively associated with the nut in a manner slightly different from the arrangement illustrated in Figs. 1, 2 and 3.

Fig. 6 is a plan view of the connector illustrated in Fig. 5 with a portion of the connector shown in section.

Fig. 7 is a perspective of the follower of the connector illustrated in Figs. 5 and 6.

Fig. 8 is a perspective of modified form of follower adapted for use with the connector shown in Figs. 5 and 6.

Fig. 9 is a modified form of the bolt of the connectors illustrated in Figs. 1, 2, 3, 5, and 6, said bolt of Fig. 9 being of tubular formation.

45 Fig. 10 is a plan view of the bolt illustrated in Fig. 9.

In the drawing, wherein are shown for the purpose of illustration, merely, several embodiments of the invention, A designates in Figs. 1, 50 2, and 3 the improved connector generally, said connector A comprising a bolt B and a nut and follower assembly C. The bolt B comprises a polygonal head portion 1 from which a shank portion 2 is extended, said bolt having formed longitudinally thereof a slot-like opening 3 which

is open at the outer face of the polygonal head portion 1 and which terminates short of the outer end of the shank portion 2 as shown to the best advantage in Figs. 1 and 2, said slot-like opening being open at opposite sides of the bolt shank. Between the outer end of the shank portion of the bolt and the adjacent closed end of the opening 3 the shank portion of the bolt B is solid as indicated by the reference character 4 in Fig. 2, and the shank portion of the bolt is externally screwthreaded throughout substantially its entire length. The shank portion of the bolt B obviously is of circular cross-section, and because of the presence in said shank portion of the straight, slot-like opening 3 extended longitudinally and transversely of said shank portion, the shank portions at opposite sides of the opening 3 are in the form of legs of segmental cross-section. Formed in and extended through the portions of the bolt B at opposite sides of the opening 3, and at points spaced inwardly of the outer face of the polygonal head portion of said bolt, is a pair of aligned openings 5 which are preferably of circular shape, the outer ends of each of said openings being flared to facilitate the introduction therewith of a conductor as will be hereinafter explained.

The nut and follower assembly C of the improved connector A is made up of a nut 6 and a follower 7, said nut being of conventional formation with the exception that it includes a relatively thin annular flange 8 which extends upwardly from the top face of the nut. The follower 7 is in the form of an element shaped as shown to the best advantage in Fig. 4; that is to say said follower comprises an elongated portion 9 which is of only slightly less width than the width of the opening 3 and which is disposed in said opening as shown in Fig. 3, and opposite end portions 10 which are extended slightly beyond opposite sides of said opening 3. The opposite end portions 10 of the follower 7 are of greater width than the portion 9 of said follower as shown in Figs. 3 and 4, and the outer faces 10' of said opposite end portions are inclined as shown in Figs. 2, 3 and 4. Preferably, though not necessarily, the portion 9 of the follower 7 has formed longitudinally thereof a substantially V-shaped groove 11 which serves as a conductor seat when the connector is in use.

In assembling the nut and follower assembly C and the bolt B to provide the improved connector A, the nut is screwed on the lower end portion of the shank portion of the bolt and the

follower is passed downwardly through the opening 3 to bring the opposite, inclined faces 10' of the follower within the annular flange 8 of the nut, which, at this time, is extended parallel 5 with respect to the axis of the nut as shown by dotted lines in Fig. 2. When the follower has been seated on the top face of the nut and within the annular flange 8, said annular flange is swaged, or otherwise displaced, to cause it to assume 10 an inclination which conforms substantially with the inclination of the end faces 10' of the follower. However the annular flange 8 of the nut is not forced into tight, frictional contact with the inclined end faces 10' of the follower 15 lower as the nut must be capable of rotation relative to the follower. When the improved connector has been assembled as described the nut may be screwed longitudinally of the shank portion of the bolt, the follower moving with the nut, in a straight-line manner, longitudinally of the opening 3.

In the use of the improved connector disclosed herein, the nut and follower assembly being located at the outer end of the shank portion 25 of the bolt B, the connector A is moved upwardly with respect to a conductor D to which another conductor E, a ground wire, for instance, is to be mechanically and electrically connected, the movement of the connector relative to the conductor D being such that said conductor is extended through the opening 3 below the aligned openings 5. An end portion of the conductor E is then extended through the aligned openings 5 and the nut 6 is rotated with respect to the shank 30 portion of the bolt to draw the conductors D and E into tight contacting relation whereby said conductors are securely connected mechanically and electrically. The force exerted against the portion of the conductor E which bridges the opening 3 of the bolt of the connector, when the nut and follower assembly is drawn upwardly on the bolt shank, will cause a slight bow to be placed in said bridging portion of said conductor as indicated at E' in Fig. 1, and the presence of 45 this slight bow will effectively resist accidental displacement of the conductor E with respect to the connector while the connector is in its conductor-clamping condition.

An important feature of the invention is that the nut and follower assembly C is always associated in operative relation with respect to the bolt B of the connector, hence the necessity for a lineman, or other person, to thread a nut on the bolt in making a connection with the connector is eliminated. Also, because the portion 9 50 of the follower 7 moves into contact with the inner face of the solid portion 4 of the bolt, when the nut and follower assembly has reached its outward limit of movement on the shank portion of the bolt, the nut and follower assembly 55 may not be undesignedly detached from the bolt. An additional feature of the present invention resides in the fact that the invention disclosed herein includes no such projected nut retainers 60 as are frequently incorporated as parts of split-bolt connectors of the type heretofore employed, and therefore the connector of the present invention may be conveniently tapered when this is desired. Still another feature of the invention 65 has to do with the solid portion 4 of the bolt shank which, because it is on the nut side of the bolt of the connector, eliminates any tendency of the legs of the bifurcated portion of the bolt to collapse because of pressure applied thereto by 70 the nut when high pressure is applied to a pair 75

of conductors being connected with the aid of the connector. In this connection it is obvious that the spaced legs at the opposite end of the bolt will not be collapsed because the nut does not move close enough to this end of the bolt to have that effect, and because the portion 9 of the follower 7, which is located between the legs, will prevent collapsing thereof.

The form of the invention illustrated in Figs. 5, 6, and 7, differs from the form of the invention shown in Figs. 1, 2, 3, and 4, in the manner of operatively assembling the nut and follower assembly. In Fig. 5 the nut 6^a is shown as provided with an upwardly projected, annular extension 12 which is provided with an annular outer divergently inclined face 12', while the follower 7^a is provided with downwardly extended tongues 13 at its opposite ends which are swaged, or otherwise displaced to cause them to loosely engage the inclined face 12' of the extension 12 20 of the nut. The form of connector illustrated in Figs. 5 and 6, is used just as has been explained in connection with the form of the invention shown in Figs. 1, 2, and 3, the nut 6^a being rotated about the bolt shank and relative to, 25 the follower 7^a, and said follower moving longitudinally of the opening 3^a as the nut is adjusted longitudinally of the bolt shank.

In Fig. 8 a form of follower 7^b is illustrated which differs from the followers shown in Figs. 1, 2, 3, 4, 5, 6, and 7, in that the follower 7^b is of substantially inverted dish-shaped formation having openings 14 formed in its top wall through which the spaced legs of the bolt shank are adapted to extend. The follower illustrated in Fig. 8 includes an annular downwardly extended flange 15 which is adapted to be swaged, or otherwise displaced, to cause it to loosely engage the inclined face 12' of the extension 12 of the nut 6^b shown in Fig. 5.

The bolt B' illustrated in Figs. 9 and 10 provides a simple bolt of tubular formation which may be economically produced by stamping or other operations. The tubular bolt B' is closed at one end by a solid wall 16, and it is provided with aligned slot-like openings 3^b extended longitudinally of the bolt, which serve the function of the opening 3 of the structure shown in Figs. 1, 2, and 3, and the opening 3^a of the structure shown in Figs. 5 and 6. Also the bolt of Figs. 9 and 10 is provided with aligned openings 5^a formed in opposed portions of the wall of the bolt which serve the function of the openings 5 of Figs. 1, 2, and 3.

I claim:

1. A connector comprising a bolt having an externally screwthreaded portion, said bolt being of solid formation at one end thereof and having spaced portions extended from said solid portion which provide a conductor-receiving opening therebetween, said solid portion of said bolt being a part of the externally screwthreaded portion of said bolt, conductor-receiving cavities formed in the portions of said bolt at opposite sides of said conductor-receiving opening, a nut and follower assembly mounted on the externally screwthreaded portion of said bolt, said nut and follower assembly comprising a nut screwthreadedly adjustable longitudinally of the screwthreaded portion of said bolt and a follower associated with said nut and having a portion which is disposed in the conductor-receiving opening of said bolt and is movable longitudinally thereof when the nut is screwthreadedly adjusted longitudinally of the bolt, and means for connecting said

follower and said nut so that the nut may rotate with respect to the follower.

2. A connector comprising a bolt having an externally screwthreaded portion, said bolt being of solid formation at one end thereof and having spaced portions extended from said solid portion which provide a conductor-receiving opening therebetween, said solid portion of said bolt being a part of the externally screwthreaded portion of said bolt, conductor-receiving cavities formed in the portions of said bolt at opposite sides of said conductor-receiving opening, a nut and follower assembly mounted on the externally screwthreaded portion of said bolt, said nut and follower assembly comprising a nut screwthreadedly adjustable longitudinally of the screwthreaded portion of said bolt and a follower associated with said nut and having a portion which is disposed in the conductor-receiving opening of said bolt 20 and is movable longitudinally thereof when the nut is screwthreadedly adjusted longitudinally of the bolt, and means for connecting said follower and said nut so that the nut may rotate with respect to the follower, said means comprising an inclined face formed on one of said elements, and a portion on the other of said elements which loosely engages the inclined face of the first mentioned element.

3. A connector comprising a bolt having an externally screwthreaded portion, said bolt being of solid formation at one end thereof and having spaced portions extended from said solid portion which provide a conductor-receiving opening therebetween, said solid portion of said bolt being a part of the externally screwthreaded portion of said bolt, conductor-receiving cavities formed in the portions of said bolt at opposite sides of said conductor-receiving opening, a nut and follower assembly mounted on the externally screwthreaded portion of said bolt, said nut and follower assembly comprising a nut screwthreadedly adjustable longitudinally of the screwthreaded portion of said bolt and a follower associated with said nut and having a portion which is disposed in the conductor-receiving opening of said bolt and is movable longitudinally thereof when the nut is screwthreadedly adjusted longitudinally of the bolt, and means for connecting said follower and said nut so that the nut may rotate with respect to the follower.

4. A connector comprising a bolt having an externally screwthreaded portion, said bolt being of solid formation at one end thereof and having spaced portions extended from said solid portion which provide a conductor-receiving opening therebetween and terminate at their outer ends in a polygonal head portion, said solid portion of said bolt being a part of the externally screwthreaded portion of said bolt, conductor-receiving cavities formed in the portions of said bolt at opposite sides of said conductor-receiving open-

ing, a nut and follower assembly mounted on the externally screwthreaded portion of said bolt, said nut and follower assembly comprising a nut screwthreadedly adjustable longitudinally of the screwthreaded portion of said bolt and a follower associated with said nut and having a portion which is disposed in the conductor-receiving opening of said bolt and is movable longitudinally thereof when the nut is screwthreadedly adjusted longitudinally of the bolt, and means for connecting said follower and said nut so that the nut may rotate with respect to the follower.

5. A connector comprising a bolt having an externally screwthreaded portion, said bolt including a bridge portion and having spaced portions extended from said bridge portion which provide a conductor-receiving opening therebetween, said bridge portion of said bolt being a part of the externally screwthreaded portion of said bolt, the portions of said bolt at opposite sides of said conductor-receiving opening having cavities formed therein, a nut and follower assembly mounted on the externally screwthreaded portion of said bolt, said nut and follower assembly comprising a nut screwthreadedly adjustable longitudinally of the screwthreaded portion of said bolt and a follower associated with said nut and having a portion which is disposed in the conductor-receiving opening of said bolt and is movable longitudinally thereof when the nut is screwthreadedly adjusted longitudinally of the bolt, and means for connecting said follower and said nut so that the nut may rotate with respect to the follower.

6. A connector comprising a bolt having an externally screwthreaded portion, said bolt being of solid formation at one end thereof and having spaced portions extended from said solid portion which provide a conductor-receiving opening therebetween, said solid portion of said bolt being a part of the externally screwthreaded portion of said bolt, conductor-receiving cavities formed in the portions of said bolt at opposite sides of said conductor-receiving opening, a nut and follower assembly mounted on the externally screwthreaded portion of said bolt, said nut and follower assembly comprising a nut screwthreadedly adjustable longitudinally of the screwthreaded portion of said bolt and a follower associated with said nut and having a portion which is disposed in the conductor-receiving opening of said bolt and is movable longitudinally thereof when the nut is screwthreadedly adjusted longitudinally of the bolt, a portion of said follower being adapted to contact with the base of said conductor-receiving opening at said solid end portion of said bolt when the outward limit of movement of the nut and follower assembly with respect to the bolt is reached to prevent complete withdrawal of said nut and follower assembly from said bolt, and means for connecting said follower and said nut so that the nut may rotate with respect to the follower.

FREDERICK W. MEBOLD.
